UNITED STATES PATENT OFFICE.

LINNAEUS E. BAKER, OF FORT WAYNE, INDIANA, ASSIGNOR TO WAYNE OIL TANK AND PUMP COMPANY, OF FORT WAYNE, INDIANA, A CORPORATION OF INDIANA.

DESIGN FOR A LIQUID-DISPENSING APPARATUS.

58,176.

Specification for Design.

Patented June 21, 1921.

Application filed October 27, 1919. Serial No. 333,851. Term of patent 14 years.

To all whom it may concern:

Be it known that I, LINNAEUS E. BAKER, a citizen of the United States, residing at Fort Wayne, in the county of Allen and State of Indiana, have invented a new, original, and ornamental Design for Liquid-DISPENSING APPARATUS, of which the following is a specification.

My design is shown in the accompanying drawings forming part hereof, in which:—

Figure 1, is an elevation of the liquid dispensing apparatus on the side ordinarily placed next to the curb, and

Fig. 2, is an elevation of the same at 90° to Fig. 1, on the liquid discharge side.

I claim:

The ornamental design for a liquid dispensing apparatus as shown.

In testimony whereof I have hereunto set my hand in presence of two subscribing witnesses.

LINNAEUS E. BAKER.
